UNITED STATES PATENT OFFICE.

NORMAN C. BEEGLE, OF PEN ARGYL, PENNSYLVANIA.

RACK.

1,075,395.

Specification of Letters Patent.

Patented Oct. 14, 1913.

Application filed February 13, 1913. Serial No. 748,160.

To all whom it may concern:

Be it known that I, NORMAN C. BEEGLE, a citizen of the United States, residing at Pen Argyl, in the county of Northampton, 5 State of Pennsylvania, have invented certain new and useful Improvements in Racks; and I do hereby declare the following to be a full, clear, and exact description of the invention, such as will enable others skilled 10 in the art to which it appertains to make and use the same.

This invention is directed to improvements in racks, and more particularly to one for holding coats.

15 The invention has for its object to provide a device of this character which may be compactly folded when not in use and carried in a valise from place to place.

A further object of the invention is to 20 provide a device of this character which is exceedingly simple in construction and one which may be manufactured at a minimum cost.

With these and other objects in view, this 25 invention resides in the novel features of construction, formation, combination and arrangement of parts to be hereinafter more fully described, claimed and illustrated in the accompanying drawing, in which:—

30 Figure 1 is a side elevation of the device. Fig. 2 is a vertical sectional view through the same. Fig. 3 is a sectional view on line 3—3 of Fig. 1. Fig. 4 is a detail perspective view of one of the coat hangers.

35 Referring to the drawing, the numerals 1, 2 and 3 designate tubular sections which are telescopically connected and may be held in adjusted positions by set screws 4 and 5 which are carried by the sections 2 and 3.

40 The lowermost section 3 is provided with sleeves 6 and 7, each of said sleeves carry set screws 8 and 9, respectively, so that said sleeves may be shifted upon the section 3. A plurality of legs 10 are also provided and 45 have their upper ends pivotally connected to the sleeve 6. Pivotally connected to the sleeve 6 is a plurality of arms 11, the outer ends of which are pivotally connected intermediate the ends of the legs 10 so that

upon adjustment of the sleeve 7 the legs 10 50 are drawn closely against the side of the sections 3 when the device is in its folded position.

55 Detachably connected to the upper end of the section 1 is a tubular section 12 which is provided with furcations 13 and between which are placed, one above the other, the members 14 which are formed from sheet metal and comprise base plates 15 and vertical side flanges 16, the ends of the base 60 plates 15 extending beyond the end edges of the flanges 16.

65 The furcations 13 are provided with registered perforations 17 in which are mounted the shafts 18, the outer ends of which terminate in hooks 19, and upon which articles of clothing may be hung, said shafts being also passed through the flanges 16 of the members 14, thereby supporting the same between the furcations 13. 70

75 The flanges 16 of each member 14 are provided near their ends with apertures 20, in which are mounted pins 20' which engage the eyes 21 formed upon the inner ends of the garment shoulder engaging loops 22, which when in their operative position rest upon the extended ends of the base plates 15, thus holding them at a proper inclination to suit the shape of the garment shoulder when the same is hung thereon. 80

85 From this construction it will be seen that the sections 1, 2 and 3 may be telescoped so as to adapt the same to be placed in a suit case and that the legs 10 may be folded against the sides of the lowermost section 3. Further it will be noted that the tubular section 12 may be removed from the section 1 and the loops 22 folded, thus producing a device which may be easily and quickly taken apart for transportation. 90

What is claimed is:—

95 A rack of the class described comprising a plurality of telescopically connected sections, a plurality of supporting legs pivotally connected to the lowermost section, a tubular member detachably connected to the uppermost section, said tubular member being provided with furcations, shafts sup-

ported by the furcations and having their ends terminating in hooks, flanged members supported by the shafts, and garment supporting loops connected to the ends of the 5 flanges of said members, as and for the purpose set forth.

In testimony whereof, I affix my signature, in the presence of two witnesses.

NORMAN C. BEEGLE.
